J. CRNOEV.
TIE HOLDER.
APPLICATION FILED MAR. 7, 1921.

1,400,663.

Patented Dec. 20, 1921.

INVENTOR.
Jan Crnoev.
BY
Frederick W. Phalen
ATTORNEY.

UNITED STATES PATENT OFFICE.

JAN CRNOEV, OF LOS ANGELES, CALIFORNIA.

TIE-HOLDER.

1,400,663.

Specification of Letters Patent. Patented Dec. 20, 1921.

Application filed March 7, 1921. Serial No. 450,335.

To all whom it may concern:

Be it known that I, JAN CRNOEV, a citizen of the Republic of Serbia, having declared my intention of becoming a citizen of the 5 United States, and a resident of Los Angeles, in the county of Los Angeles and State of California, have invented certain new and useful Improvements in Tie-Holders, of which the following is a specification.

10 This invention relates to an improved tie holder and has for its object to provide a device upon which a four-in-hand tie is tied and having means for attaching the device upon a collar button with said means adjustable to vary the relative height of the tie; and to provide means adapted to engage and hold down the adjacent ends of a collar.

15 Various other objects and advantages will be more fully apparent from the following 20 description of the accompanying drawings which form a part of this disclosure, and which illustrate a preferred form of embodiment of the invention.

Of the drawings:

25 Figure 1 is a front elevation of the device and tie as worn.

Fig. 2 is a perspective view of the tie holder.

30 Fig. 3 is a side elevation of the device and 35 tie showing its engagement with the collar button.

Fig. 4 is a detailed view of the spring hinge connection.

Fig. 5 is a perspective view of a modified 40 form of the device.

The device has a body member 1 which is preferably formed of a single piece of wire stock bent to the form illustrated with the ends twisted together and terminating 45 with opposed coiled spring ends 2 forming a hinge journal for a connecting clevis member 3. The tension of the wire stock tends to separate the coiled ends 2 and the outer coil of each end is formed to provide a 50 rounded cam or hump 4 with which the adjacent limb of the clevis member 3 engages and over which it rides when swung from one position to another. In the open position, as illustrated in Figs. 2 and 4, the 55 limbs of the member 3 are positioned upon one side of the companion humps 4 and when swung to the closed position shown in Fig. 3 the limbs ride over said humps to positions on the opposite sides thereof, the 60 coiled ends 2 being forced toward each

other, as indicated in dotted lines in Fig. 4; during the movement of the member 3. This hinge connection functions to frictionally maintain the member 3 in either open or closed position.

60 Hingedly joined to the opposite end of the member 3 is a frame 5 providing two parallel slide limbs and slidable upon said limbs is a supporting member 6. The member 6 is preferably made of wire stock 65 formed to provide a transverse bridge limb 7 with the ends wound around the limbs of the frame 5 in coil spring formation and then transversely crossed to form a second bridge limb 8 substantially parallel with the 70 limb 7 and spaced therefrom to form an intermediate receiving throat. The ends of the wire stock are again wound around the limbs of the frame 5 and project outwardly and are provided with sharpened hooked 75 ends 9.

In use, the four-in-hand tie 10 is tied upon the body member 1 and the clevis member 3 swung to closed position against the back surface of the tie. The tie holder and tie are then inserted under the collar 11 as shown in Fig. 1 and the supporting member 6 engaged over the collar button 12, (see Figs. 2 and 3), the hinge limbs 7 and 8 being separated by the head of the collar button during the insertion thereof in the receiving throat and then returning to normal as the head of the collar button passes through. This form of spring snap supporting member permits engagement with 80 any ordinary form or size of collar button.

85 After engagement with the collar button or before, the supporting member 6 may be adjusted along the frame 5 to regulate the height of the tie relative to the position of the collar button so as to bring the tie to a proper height relative to the height of the collar.

90 With the tie properly positioned to be worn with a soft collar, the opposite corners of the collar may be hooked upon the hook ends 9 while with a hard collar said hook ends are not utilized.

95 This mechanism provides a tie holder having a supporting means adapted to engage a collar button and be slidably adjusted to regulate the height of the tie and having means for engaging the ends of a collar.

100 In the modified form of device shown in 110

Fig. 5 the supporting member is slidably carried upon the limbs of the clevis member, thereby eliminating frame 5.

I claim:

5. 1. A device of the class described combining a substantially T-shaped body with its shank formed to provide opposed cam projections yieldingly urged outwardly, a member hingedly connected to the shank and co-operating with the cam projections to yieldingly maintain said member in closed position toward the shank or in open position away from the shank, and means carried by said member and adapted to engage a collar button.
10. 2. A device of the class described combining a substantially T-shaped body with its shank formed to provide opposed cam projections yieldingly urged outwardly, a member hingedly connected to the shank and co-operating with the cam projections to yieldingly maintain said member in closed position toward the shank or in open position away from the shank, a second member hingedly connected to the free end of the first member, and means carried by said second member and adapted to engage a collar button.
15. 3. A device of the class described combining a substantially T-shaped body upon which a four-in-hand tie may be tied, a member hingedly connected with the lower end of the body and providing relatively spaced parallel limbs, and a supporting member slidable on said limbs and having spaced transverse bridge limbs forming an intermediate throat with the bridge limbs yieldingly maintained in spaced relation.
20. 4. A device of the class described combining a substantially T-shaped body upon which a four-in-hand tie may be tied, a clevis member hinged to the lower end of the body, a frame hinged to the clevis member, and a supporting member slidable on the frame and having a receiving throat adapted to receive the head of a collar button.
25. 5. A device of the class described combining a substantially T-shaped body upon which a four-in-hand tie may be tied, a member hingedly connected to the lower end of the body, a supporting device slidable on said member and adapted to engage a collar button, and collar engaging devices carried by the supporting device.
30. 6. A device of the class described combining a substantially T-shaped body upon which a four-in-hand tie may be tied, a connecting member hinged to the lower end of the body, a frame hinged to the upper end

of the connecting member, a supporting member slidable on the frame and adapted to engage and be supported by a collar button, and collar engaging tangs carried by the supporting member.

7. In a device of the class described the combination with a substantially T-shaped body formed of wire having the ends coiled to provide hinge bearings at the lower end of the shank and tensioned to urge said bearings away from each other, of a member engaging into said bearings, and means carried by said member and adapted to engage a collar button, the bearings having cam projections co-operating with said member to yieldingly maintain it in closed or open position toward or away from the shank.

8. In a device of the class described the combination with a substantially T-shaped body formed of wire having the ends coiled to provide hinge bearings at the lower end of the shank and tensioned to urge said bearings outwardly, of a member engaging into said bearings, a second member hingedly connected to the free end of the first member, and means carried by the second member and adapted to engage a collar button, the bearings having cam projections co-operating with said first member to yieldingly maintain it in closed or open position toward or away from the shank.

9. A device of the class described combining a body upon which a neck-tie may be tied, a member hingedly connected to the body, and a supporting element carried by said member and adapted to engage a collar button, said element being slidably connected to said member whereby the body carrying the tie may be vertically adjusted while said element is in engagement with the collar button.

10. A device of the class described combining a body upon which a neck-tie may be tied, a member hingedly connected to the body, a second member hingedly connected to the first member, and a supporting element carried by the second member and adapted to engage a collar button, said element being slidably connected to said second member whereby the body carrying the tie may be vertically adjusted while said element is in engagement with the collar button.

Signed at Los Angeles, California, this 25th day of February, 1921.

JAN CRNOEV.
